QUADDING AND CENTERING DEVICE FOR
TYPOGRAPHICAL CASTING MACHINESLouis Rossetto, Flushing, and Gino F. Squassoni,
Corona, N. Y., assignors to Mergenthaler Linotype Company, a corporation of New York

Application September 9, 1950, Serial No. 184,071

31 Claims. (Cl. 199—50)

This invention relates to quadding and centering devices for typographical casting machines and more particularly to devices of the type disclosed in the Frolander Patent No. 1,971,400, the Hilpman Patent No. 2,255,254, the Turner application Serial No. 80,887, filed March 11, 1949, now U. S. Patent No. 2,639,027, and the Rossetto application Serial No. 183,033, filed September 2, 1950. The present improvements, which will best be understood from the detailed description to follow, are intended to increase the efficiency of such quadding and centering devices and to extend their scope of operation, although it may be stated here that one of the characteristic features of the improvements is an electro-mechanical control which may be operated either manually or automatically by a Teletypesetter unit to condition the machine for a quadding operation with either jaw, for a centering operation with both jaws, for a regular machine operation which involves no quadding or centering, as well as for an automatic quadding operation with the right-hand jaw when a composed line falls short by a predetermined amount of the full length of line for which the machine is set.

Referring to the drawings:

45 Figs. 36 and 36-A contain the circuit diagram for the present invention.

In the regular operation of the machine (see Fig. 1), the matrices X and expansible spacebands Y are composed in line in the assembler 50 2 under the restraining influence of the line resistant 3 of the assembler slide 3^a, which latter can be set in a manner to be later explained for lines of different length. After the line has been composed, the assembler is raised to position the line between the left-hand finger 4 and the relatively short right-hand finger 5 of the

line delivery carriage 6, which thereupon moves to the left and transfers the composed line through the intermediate delivery channel 7 into the vertically movable line transporter or first elevator 8 slidably mounted in the vise frame 9. Upon receiving the composed line, the first elevator immediately descends to position it between the left-hand jaw 10 and the right-hand jaw 11 and in front of a slotted mold, which latter then advances from the rear and into contact with the line and the two clamping jaws for the slug casting operation, the line prior to the casting operation being aligned with the mold and properly justified when the machine is operating under the usual conditions. After the slug has been cast, the mold is carried from its horizontal casting position to a vertical ejecting position by a three-quarter turn of the mold disk 12 (see Fig. 29); in the meantime, the first elevator is being raised to the upper transfer level where the composed line is shifted therefrom to the right by the operation of the usual transfer slide into the upper transfer channel 13 preparatory to the separation of the matrices from the spacebands for delivery to their individual storage magazines. The first elevator then is lowered and finally comes to rest in its original or line receiving position just before the machine cycle is completed.

The line clamping jaws 10 and 11 are operable to cooperate with lines of less than full length so as to cast slugs with blank spaces at either end, as for "quadding," or at both ends for "centering." For this purpose (Fig. 2), the two jaws 10 and 11 are movable toward and from each other by a vertically movable rod 14 which may be connected at its upper end to the respective jaws through the medium of two similar oppositely disposed bell crank levers 15 and 16 pivoted at 15^a and 16^a, respectively, to the vise frame 9. The longer arm of the lever 15 (see Figs. 1 and 2) is connected by the link 17 directly to the support 18 for the right-hand jaw 11, while the longer arm of the lever 16 is connected by the link 19 to the banking block 20 for the left-hand jaw 10, which latter is capable of adjustment toward and from the opposing right-hand jaw 11 to provide for the proper handling of composed lines of different lengths in the normal or regular operation of the machine.

In providing for the connection and disconnection of the rod 14 with and from the jaws 10 and 11, it is equipped (Figs. 1, 2 and 11) at its upper end with the annularly grooved collar 21 formed for engagement with diametrically opposed pins 22 and 23 protruding inwardly from the extremities of the shorter arms of the jaw actuating levers 15 and 16, respectively. The rod 14 is mounted to slide in suitable bearings of the vise frame 9 and is provided with the serrated collar or rack 24. In the present instance, the collar 21 is keyed or otherwise secured to the rod 14 and the latter is rotatable in opposite directions in order to set the collar in different angular positions so as, in this way, to establish an operative connection between the rod and either jaw for quadding, or between the rod and both jaws for centering.

The movement of either or both of the jaws during a quadding or centering operation is effected by the upward movement of the rod 14. Since the justification of composed lines in standard machines takes place during each casting cycle immediately after the line has been positioned between the clamping jaws, members 75

of the justifying mechanism in performing their normal functions are used advantageously to effect such upward movement of the rod 14. Part of this mechanism is shown in Figs. 2, 5, 6 and 11 and includes, generally, the horizontal spaceband thrust bar 25 supported at its opposite ends by two vertical rods 26 and 27 slidably mounted in the vise frame 9, the spring-actuated fore-and-aft lever 28 controlled by cam action from the main drive shaft 29 (see Fig. 29) of the machine, and the second spring-actuated fore-and-aft lever 30 also controlled from the main drive shaft of the machine. Generally speaking, there are two separate operations included in the justification of a composed line; the first is a preliminary operation, involving the upward movement of the long fore-and-aft lever 28 which, through the medium of a sleeve 31 is splined to the rod 26 and arranged to engage a collar 32 fixed thereto, raises the thrust bar 25 in a canted position; the second is the final operation, involving the upward movement of both levers 28 and 30 in synchronism, the lever 28 serving as before to drive the rod 26 upwardly, and the lever 30 serving to drive the companion rod 27 upwardly through the medium of a sleeve 35 splined to the rod 27 and adapted to engage a collar 36 fixed thereto. The effect of the synchronous movement of the two levers 28 and 30 is to drive the thrust bar 25 upward in a horizontal position for the final justification of the composed line.

According to the present improvements, the fore-and-aft levers 28 and 30 are utilized to control the upward movement of the vertical rod 14, and they do so by the action of a pair of pawls 33 and 34 cooperating with the rack 24. As shown in Figs. 2, 5 and 6, the pawl 33 is loosely mounted in an upstanding portion of the sleeve 31 and, in its lowermost or inoperative position, it is adapted to be held out of engagement with the rack 24 by an adjustable set screw 33^a adapted to bear against a shelf on the vise frame of the machine. When the sleeve 31 is moved upwardly, however, the pawl 33 falls by gravity into engagement with the rack and then drives the vertical jaw closing rod 14 upwardly. The pawl 34, on the other hand, is oppositely disposed with respect to the pawl 33 and the rack 24 and is loosely mounted on a centrally pivoted lever 37 at a point between the pivot and the left end thereof. A small arm or spur member 38 is connected to the pawl 34 and is provided with an adjustable set screw 40 adapted, in the normal position of rest of the parts, to seat on a ledge of the vise frame 9 to withhold the pawl 34 from engagement with the rack 24. The lever 37 carries an antifriction roller at its right end which is adapted to be engaged by the upper surface of a plate 35^a, screwed or otherwise attached to the sleeve 35. When, therefore, the lever 30 is actuated and the lever 37 is raised by the plate 35^a sufficiently to unseat the set screw 40, a spring 39 which pulls downwardly on the spur 38 rocks the pawl 34 into engagement with the rack 24, and the further upward motion of the plate 35^a then serves to drive the jaw closing rod 14 upwardly.

Pivots attached to a bracket arm 41 on the vise frame 9 is a split lever having arms 42^a and 42^b connected by a spring 42^c which serves to maintain a lug on the arm 42^b against an adjustable screw 42^d carried by the arm 42^a (see Fig. 11). The lowermost extremity of the arm 42^b is pivotally connected by a short link 44 to a long

more or less vertically disposed arm 43, pivotally suspended in the vise frame. The arm 42^a carries an antifriction roller which is adapted to bear against the upper surface of the rack 24 and serves, through the arrangement just described, to regulate the speed with which the jaw closing operation takes place in order to prevent damage to the matrices.

The operation of the vise closing rod 14 can now be explained. With a line of matrices in position for a quadding or centering operation and the mold advanced against the faces of the matrices so positioned, the cam-controlled spring-actuated lever 28 is permitted to rise, said rise corresponding to the upward movement of the lever for first justification of composed lines in regular operation. During its upward movement, the lever 28 moves the sleeve 31 upwardly, allowing the pawl 33 first to fall into engagement with the rack 24 and then to effect the closing of the jaw or jaws against the composed line, any excessive shock being, as explained, taken up by the spring 42^c. After the above described operation, the long fore-and-aft lever 28 is forced downwardly by the control cam and the mold recedes away from the faces of the matrices. The jaw closing rod 14, however, although relieving the force initially exerted in closing the jaws on the composed line, nevertheless remains in its upward position due to the balance of the system of levers and the weight of the jaw or jaws. The casting operation is now about ready to take place, and, as in the ordinary operation of the machine, the mold bearing disk 12 is advanced, carrying the mold once again into contact with the faces of the matrices, the melting pot 45 (see Fig. 29) is tilted forwardly against the back of the mold, and finally both of the spring-actuated cam-controlled justification levers 28 and 30 are permitted to rise together to bring both pawls 33 and 34 into play against the rack 24, all in the manner above described. At the beginning of this final jaw closing operation, since the vertical rod 14 is already in raised position as a result of the preliminary action of the lever 28 and the pawl 33, as just explained, the joint action of the pawls 33 and 34 on the rod 14 brings the full pressure of the two justification lever springs against the composed line of matrices. With the full pressure thus applied to the line, molten metal is forced into the mold for the slug casting operation.

After the casting operation, the justification levers 28 and 30 are both returned to their downward position of rest by the further rotation of their respective cams, and the mold disk 12 is rotated through a three-quarter turn to carry the mold to the vertical slug ejecting position; meanwhile, as explained above, the first elevator 8 lifts the matrices to the transfer channel. The present invention makes use of the ascent of the first elevator for the purpose of restoring the jaws to their original position of maximum separation. Toward this end (see Fig. 11), the first elevator 8 is provided with a beveled plate or cam 46, the inclined surface of which is adapted during the ascent to engage an antifriction roller 47 carried at the lowermost extremity of the pivoted arm 43, forcing the arms 42^a and 42^b to pivot in clockwise directions and causing the arm 42^a to depress the vertical rod 14 to its normal or lowermost position of rest. Any resulting shock caused by this return action will, of course, be taken up by the spring 42^c.

To determine the lowermost and normal posi-

tion of rest of the rod 14, the lower end of the said rod, as shown in Figs. 11 and 12, is provided with an annular groove 48 and a spring-pressed plunger 49, built into the vise frame 9, is adapted to enter said groove when the rod is in the lowermost position. The lower wall 48^a of the groove 48 is beveled to disengage the plunger 49 during the upward movement of the rod.

As already explained, the rod 14 is equipped at its upper end with the annularly grooved collar 21 formed for engagement with the pins 22 and 23 protruding inwardly from the extremities of the shorter arms of the jaw actuating levers 15 and 16, respectively. The rod 14 is rotatable in opposite directions, in order to set the collar in different angular positions so as, in this way, to establish an operative connection between the rod and either jaw for quadding, or between the rod and both jaws for centering. During the regular operation of the machine (which involves no quadding or centering), the vertical rod 14 is not required to function, since the jaws 10 and 11 are set to receive certain length lines and the lines are expanded between the jaws during justification. The rack 24 is, therefore, provided (see Fig. 6) with diametrically opposite grooves and the rod rotated to bring the grooves in line with the pawls 33 and 34; consequently, the pawls will have no effect whatsoever on the rod 14. On the other hand, the lower section of the collar 21 is provided with two large notches so shaped and disposed that when the right-hand jaw 10 is to be connected alone to the actuating rod 14, the collar 21, by a partial rotation of the rod, is set to the position shown in Fig. 8 so as to locate one of the notches in line with the pin 22; the collar 21 will thus engage the pin 22 to operate the right-hand jaw, but it will clear the pin 23 so that the left-hand jaw will not be thereby actuated. When both jaws are to be connected to the rod 14 for a centering operation, the collar 21 by another partial rotation of the rod will permit the lower section to engage both pins 22 and 23, as shown in Fig. 9. Finally, when the left-hand jaw 11 is to be connected to the rod 14 for operation, the collar 21 by further rotation of the rod 14 is set in the position shown in Fig. 10 to bring the other of said notches in position to clear the pin 22 while allowing the collar to engage the pin 23. The position of the collar 21 is also shown in Fig. 7 as set for regular operation in order to afford a complete understanding of this control mechanism, but since, as explained above, the rod 14 is not operated (see Fig. 6) the position of the collar is immaterial. The lower segment of the collar 21 is also provided with three smaller notches, one of which is adapted, in each of the three positions for quadding and centering (see Figs. 8, 9 and 10) to be aligned with a guide 9^a formed in the vise frame 9 of the machine to prevent the rotation of the collar during the rise of the rod 14.

According to the present improvements, the collar 21 may be set in its various angular positions either manually or automatically in response to signals contained in a control tape; in addition, the manual means employed may be either mechanical or electrical. The manually controlled mechanical means, as best shown in Figs. 2, 3 and 4, include pulleys 50 and 51 connected by a flexible band or wire 52 and guides 53 therefor. The pulley 50 is keyed or splined to the rod 14 so that the rotation of the pulley by the wire is possible while still permitting the rod to be moved upwardly and downwardly in a vertical direction

with respect to said pulley. The vise frame 9 should, of course, be provided with suitable eyelets to accommodate the wire 52. The pulley 51 is adapted to be rotated by a hand lever 54 through a long shaft 55 and gears 56^a and 56^b. The shaft 55 is equipped with an indicator 57 to be used in association with a graduated scale 53 as a guide to the operator in making the various settings of the control rod 14, and a spring-pressed plunger 59 is adapted to engage notches in the gear segment 56^b to maintain the setting (see Fig. 3).

The manually controlled electrical means for setting the control rod can be briefly described at this point by reference to Figs. 26 to 28 and Figs. 32 and 33. A push-button control box 60, as shown in Figs. 32 and 33, is mounted alongside the keyboard 61, the five push buttons 60-A to 60-E corresponding to the controls for "regular" operation, "automatic" right-jaw quadding of short lines, right-jaw quadding, centering and left-jaw quadding operations, respectively.

The push-button control device can be of any type or design, but preferably is of a type according to which the setting of any particular button releases all the previous settings. As shown in Fig. 33, and as will be later explained with reference to the circuit diagram, the control box 60 contains signal lights 62 and 63, the former to indicate power supply and the latter to indicate Teletypesetter operation, and a switch 64 which can be set either for manual (electrical) or Teletypesetter control.

The electrical push-button control for setting the rod 14 includes primarily a pulley 65, a long flexible wire or band 66 passing around the pulley and over grooved rollers 65^a, a short flexible wire or band 66^a, a slotted slide 67, and three solenoids or equivalent electrical elements A, B and C (see Figs. 26 and 28) enclosed in a box or housing 68. The slide 67 is attached at its upper end to one end of the wire 66 and at its lower end to one end of the wire 66^a, being mounted for movement in an upward and downward direction between vertical guides 67^a and 67^b. The maximum upward position of the slide is determined by the lower portion of the eyelet 66^a for the wire 66, and its maximum downward position is determined by the upper portion of the eyelet 66^b for the wire 66^a. The normal or regular position of the slide is its most upward position for regular machine operation, and the distance it is moved downwardly from such normal position determines the setting of the control rod for right-jaw quadding, centering, and left-jaw quadding in that order, the left-jaw quadding position corresponding to the maximum downward position of the slide. At its end remote from the slide, the wire 66 is attached to a tension spring 68 which serves to keep the slide in the normal or regular upward position. And at its end remote from the slide, the wire 66^a is connected to an arm 70 pivotally mounted on a lever 71 which is loosely held on a shaft 72 (see Fig. 28). The lever 71 is connected by means of a torsion spring 73 to another lever 74, which latter is fixed to the shaft 72. The lever 74 carries an antifriction roller 74^a adapted to be engaged by the beveled surface 75^a of a cam plate 75 carried by the first elevator. It can be thus seen that the descent of the first elevator will rotate the lever 74 in a counterclockwise direction and effect a like rotation of the lever 71 through the medium of the spring 73, the arm 71 serving to pull the slide 67 downwardly by contact with an adjustable set screw 70^a on the

arm 70. Since the spring 73 provides a yielding connection between the levers 74 and 71, the slide 67 can be stopped at any predetermined position to effect the setting of the rod 14. When the elevator rises to transport the matrices and space-bands for distribution, the slide 67 is returned to normal or upward position by the spring 69.

The amount of vertical displacement of the slide 67, and consequently the setting of the collar 21, is controlled by spring-pressed plungers A¹, B¹ and C¹ connected to the armatures a, b and c of the solenoids A, B and C, respectively. As shown in Fig. 26, the slide 67 is provided with a round hole a¹ which is adapted to be engaged by the plunger A¹ to hold the slide in its uppermost position corresponding to the regular setting of the collar 21 as shown in Fig. 7; with a somewhat elongated hole or slot b¹ which is adapted to be engaged by the plunger B¹ and allows a partial downward displacement of the slide when the plunger A¹ is removed from the hole a¹ for the purpose of setting the collar 21 in the right-jaw quadding position, as shown in Fig. 8; and with a still more elongated hole or slot c¹ which is adapted to be engaged by the plunger C¹ and allows a further downward displacement of the slide when the plungers A¹ and B¹ are removed from the holes or slots a¹ and b¹ for the purpose of setting the collar 21 in the position shown in Fig. 9 for centering. The plungers A¹, B¹ and C¹ are withdrawn from engagement with their respective holes or slots by the energization of the respective solenoids A, B and C; and, of course, when all three are energized, the slide 67 is permitted to be shifted downward to its maximum lowermost position, thereby setting the control collar 21 to the left-jaw quadding position as shown in Fig. 10. The selective operation of the solenoids is controlled by the push buttons 60-A, 60-C, 60-D and 60-E of the control box 60, the appropriate button being pressed after the particular line has been composed in the assembler 2. The circuits for the energization of the solenoids are thereupon conditioned for operation, and, when the line of matrices is presented in casting position by the descent of the first elevator 8, the rotation of the first elevator operating cam 8^a closes a switch 182 (see Fig. 29) to energize the appropriate solenoid. During the ascent of the line after the casting operation, a switch 184 is opened, thereby wiping out the particular signal. A more detailed description of the above operation will be presented in connection with the circuit diagram contained in Figs. 36 and 36A.

The remaining button 60-B, when actuated, serves to condition the electrical system for "automatic" quadding short lines with the right-hand jaw while permitting full length lines to be cast as in regular operation. Toward this end, a line measuring device, denoted generally by the reference numeral 80 and enclosed within a box or housing 82, is attached to the left-hand side of the machine just beyond the first elevator 8 when it occupies its line receiving position. Protruding from the box toward the right is a plunger rod 81 arranged with its right end in the line of travel of a block 4^a to which the long left-hand finger 4 of the line delivery carriage is attached (see Figs. 1, 18 to 20). The head 81^a at the left end of the rod 81 is situated in the housing 82 and, as the line delivery carriage fingers 4 and 5 convey the line of matrices from the assembler 2 to the first elevator 8, the rod 81

is pushed in a leftward direction through a distance corresponding to the length of the line. Also situated in the housing 82 is a block 83 threaded to a rotatable screw 84 and supported by a rail 85, the block being adjustable to the right or the left by the rotation of said screw. The block 83 carries an upstanding bracket 83^a on which is mounted an electrical switch 86 and a pivoted make-break arm 87 carrying a roller 87^a at its free end. Also mounted on the movable block 83 is a rotatable three segment member 88^a, 88^b and 88^c which is acted upon by a center overthrow spring 89 to maintain it in contact with a stop pin 83^b and normally in an inoperative position, as shown in Figs. 18 and 19. The segment 88^a carries a cam 88^{aa} which, when a line of matrices is over a predetermined length, is brought into contact with the roller 87^a of the arm 87 and effects the closing of the switch 86. This switch closing operation is effected by the engagement of the rod 81 with the second segment 88^b, which when rotated sufficiently causes the overthrow of the spring 89, a further stop pin 83^c limiting the rotation. After the line has been delivered into the first elevator 8, the rod 81 is restored to its normal or rightward position by a spring-urged tape 90 and, as the rod 81 begins its return, the collared head portion 81^a engages the third segment 88^c and rotates the cam bearing segment 88^a back to normal or inactive position with the aid of the spring 89. By way of explanation, when the push button 60-B is set for "automatic" quadding, if the line is long enough to effect the closing of the switch 86, the circuit is unconditioned for operation, as will be more fully explained in connection with the circuit diagram contained in Figs. 36 and 36A, and the collar 21 is maintained in position for regular operation. If, on the other hand, the line is too short for regular casting and, therefore, fails to close the switch 86, the circuit is conditioned for the energization of the solenoids A and C to effect the rotation of the collar 21 to right-jaw quadding position.

In accordance with the present improvements, adjustments of the line measuring device 80 are possible, not only when the settings of the assembler slide 3^a and the vise jaws 10 and 11 are changed to accommodate lines of different length, but also to vary the length of line that will be automatically right-jaw quadded, simultaneously with or independent of the settings of the vise jaws and the assembler slide. Thus, for example, the assembler slide and vise jaws may be set to accommodate lines of 14 ems and the line measuring device 80 set to automatically right-jaw quad lines 2 ems short thereof (that is, lines under 12 ems). If, then, it is desired to cast from lines of 30 ems, the assembler slide, vise jaws and line measuring device must all be set accordingly; however, since lines of 30 ems are usually capable of greater expansion than lines of 14 ems, it would hardly be necessary to quad all lines that are only slightly under 28 ems. For this reason, adjustment of the line measuring device is possible to provide for right-jaw quadding of lines more than 2 ems short, say, for example, 3, 3½ or 4 ems short, without changing the settings of the assembler slide or the vise jaws.

Toward these ends, a rotatable adjusting wheel 92 (see Fig. 13) is mounted on the right-hand side of the vise frame 9 and is adapted to rotate a screw 93 associated with the banking block 20 of the left-hand jaw 10 for the

purpose of adjusting the left-hand jaw toward or from the right-hand jaw 11 through an arrangement of gears 92^a, 94, 95, 96 and 97, and a rotatable shaft 98 having a telescopic connection with the screw, said shaft extending loosely through the support 18 for the right-hand jaw 11 and having no effect thereon. The right-hand extremity of the shaft 98 is provided with a small bevel gear 99 in constant mesh with another bevel gear 100. The gear 100 is connected by a flexible shaft extending through a cable 101 to a gear 102 (see Figs. 14 to 16); the gear 102 is adapted to mesh with a gear 103, and both of said gears are enclosed in a housing 104 mounted on the front face plate 105 of the machine. As shown, the upper part of the housing 104 is provided with grooved lugs 104^a and 104^b which serve as guides for the assembler slide 3^a. The gear 103 is pinned to the shaft of a rotatable screw 106, to which is threaded an adjustable stop member 107 adapted to prevent the assembly of lines of greater length than that for which the jaws are set to accommodate. As the matrices are individually composed against the line resistant 3, the slide 3^a will be moved accordingly in a leftward direction against the tension of a spring until a screw 108 mounted on the slide comes into contact with the stop 107. Obviously, however, the line should be completed just short of this condition. As will now be clear, both the stop 107 and the left-hand jaw 10 are adjustable by the wheel 92, the various gear arrangements being such that the movement of the jaw 10 through a distance x (Fig. 13) will effect a like movement of the stop member through the same distance x (Fig. 14).

If by chance the composed line is too tight, slightly exceeding the setting of the jaw by one or two matrices, the present improvements include means for slightly backing off the stop member 107 to facilitate the removal of the extra matrix or two. The screw 106 is therefore rotatably and shiftably supported in bearings 104^c and 105^a, the former being integral with the housing 104 and the latter being affixed to the face plate 105. A plunger 111, extending from the right-hand end of the screw 106, is spring-urged in a rightward direction to maintain the screw banked against the bearing 105^a, and a small pivoted locking lever 109, held in locked position by a spring 110, is adapted to engage a groove in the left-hand extremity of the screw 106, the shoulder 106^a (see Fig. 14) serving to prevent movement of the screw in a leftward direction. When the lever 109 is pivoted out of locking position, however, the screw 106 can be shifted endwise to the left slightly by the depression of the plunger 111 or by simply pulling the line resistant 3 to the left. The stop 107 will thereby be backed away from the screw 106, loosening the line to permit the operator to remove the last matrix or two with ease.

The hand wheel 92 not only effects the setting of the assembler stop 107 and the vise jaw 10 but, in addition, it operates to simultaneously change the setting of the line measuring device 80. It has already been explained how the rotation of the hand wheel 92, through the gear arrangement 92^a, 94, 95, effects the rotation of the gear 96. As best shown in Figs. 17 and 21, the gear 96 is provided with internal gear teeth which are adapted to mesh with and rotate a small gear 112 fastened to a shaft 113. Another small gear

11

114 of double width is likewise fastened to the shaft 113 and is adapted to mesh with internal gear teeth of a bevel gear 115. The bevel gear 115 is in constant mesh with another bevel gear 116 which, through the medium of a long flexible shaft housed in a cable 117, serves to rotate the aforementioned screw 84 to adjust the block 83 thereon.

It will now be seen that, when a different length line is to be cast, the hand wheel 92 is operated to change the settings of the vise jaws, the assembler stop, and the line measuring device simultaneously. As best shown in Figs. 17 and 23, a scale 119, mounted in a housing 120, is provided as a guide in making these settings. The gear 96 is fastened to a rotatable screw 121 (see Figs. 24 and 25) and a marker or indicator 122 threaded thereon, so that when the gear 96 is rotated by the wheel 92 the marker 122 will be moved in relation to the scale 119. The scale is preferably graduated in ems to correspond with the length of line to be cast and a single revolution of the screw 121 will move the marker 122 one em along the scale 119; the gear arrangement is such, however, that a single revolution of the wheel 92 will rotate the screw 121 through three revolutions. Also attached to the screw 121 is a dial 123 with 12 graduations corresponding to point settings (12 points equals 1 em) for finer adjustments.

As already stated, it sometimes is desirable to change the setting of the line measuring device 80 independently of the vise jaws and line stop in order to vary the length of line that will be automatically right-jaw quadded. For this purpose, a knob 124 (see Figs. 1, 13, 23 and 25), pinned to the shaft 113, may be pulled to the right against spring tension to shift the gear 112 out of engagement with the gear 96 (the shaft of the screw 121 being provided with an enlarged bore to accommodate the gear 112) and, at the same time, to shift the wide gear 114 to the right into engagement with a gear 125 (see Fig. 21) while still maintaining its engagement with the bevel gear 115. The shaft 113 is, therefore, free to revolve inside of and independently of the screw 121, the only connection between the two being through the disengaged gears 112 and 96. It will be remembered that the gear 115 is adapted to rotate the screw 84 to adjust the block 83 of the line measuring device 80. The gear 125 is provided with a dial 126 having eight half-em graduations thereon, reading from 0 to 4 ems, so that the line measuring device 80 can be independently set with precision to regulate, at the will of the operator, the length of line short of full length that is to be automatically quadded. For example, if the jaws and assembler stop were set for lines of 27 ems and the dial 126 were set at 3 ems (assuming, of course, that the machine is being operated with the push-button control set for "automatic quadding"), any line under 24 ems would be automatically quadded while lines over that limit would be cast regularly. Obviously, the knob 124 in its normal or leftward position can be employed for finer settings of the jaws, assembler stop and line measuring device, employing the dial 123 (which reads "points" or $\frac{1}{12}$ ems) or the scale 119 (which reads "ems").

For conveniently locking and locating the setting device in any desired position, the right-hand end of the housing 120 is provided with a plurality of holes 120^a, preferably twelve in num-

12

ber to correspond to "point" settings, and the knob 124 is provided with a pin 124^a slidably mounted therein for insertion in or removal from the appropriate hole corresponding to that particular setting. The pin 124^a is adapted to be shifted between operative or locked position and inoperative or unlocked position, and, to facilitate the location of the pin in either position, the shaft thereof is provided with two adjacent grooves or detents 124^b and 124^c and a single spring-pressed ball 124^d adapted to engage the groove 124^b in the unlocked position and the groove 124^c in the locked position. The separation between the said grooves is preferably beveled on either side to facilitate the movement of the pin from one position to the other.

It might also be mentioned that the above described setting mechanism can be employed to simultaneously adjust the Mohr saw mechanism, a standard well known product which is adapted to be attached to line casting machines for the purpose of cutting off the blank end portions of cast slugs. For purposes of the present invention, it suffices to say that the regular vertical adjusting screw 127 of the Mohr saw is provided at the uppermost extremity thereof (see Fig. 13) with a bevel gear 128 which is adapted to engage a bevel gear 129 mounted on a horizontally disposed shaft 130. A gear 131 on the shaft 130 is in mesh with the gear 92^a, so that the Mohr saw can be adjusted simultaneously with the left-hand jaw 10, the assembler stop 107, and the line measuring device 80.

In the regular operation of the machine (which involves no quadding or centering) the jaws 10 and 11 are relatively immovable and the line of matrices justified therebetween by expandible spacebands. Inasmuch as the molten metal is forced into the mold under considerable pressure by means of a pump plunger 136 (see Figs. 30 and 31) through a spring-operated cam-controlled bell crank lever 137, it is extremely important that the line be fully expanded between the jaws to prevent "squirts." As a conventional safety measure to prevent the above mentioned condition, the more or less horizontally disposed arm of the bell crank lever 137 is provided with a projection 137^a under which a pivoted pump plunger stop 133 is normally adapted to rest. If a line has been sufficiently expanded during justification, the right-hand jaw 11 will yield slightly and, through a contact set screw 139, actuate a pivoted lever 140 to withdraw the stop 133 from the downward path of the projection 137^a. While this safety attachment is satisfactory for regular machine operation, it is not entirely satisfactory for quadding and centering operations and particularly quadding and centering operations involving a closing movement of the right-hand jaw which leaves the pump plunger stop active. For these latter operations, therefore, an electrical safety device controlled from the left-hand jaw is provided. Thus the stop 133 is adapted to be released by the operation of a rotary solenoid or equivalent electrical element 141. For this purpose, as shown in Fig. 36, a voltage supply is tapped off a transformer 142 and converted into direct current by a rectifier 143. The left-hand vise jaw 10 has a spring-pressed plunger 144 (see Fig. 30) built into it, and when sufficient pressure is exerted by the jaw on the line of matrices, the plunger 144 is caused to yield to close a switch 145 (also built into the jaw 10) to complete the necessary circuit for the opera-

tion of the solenoid 141. Obviously, if the pressure exerted by the jaw 16 against the line is not sufficient to close the switch 145, it would be unsafe to cast, and, consequently, the circuit would not be completed. A resistor 146 and a condenser 147 are tied in parallel with the pump stop solenoid 141 (see Fig. 36A) to prevent sparking when the switch 145 is opened. It should be explained that the left-hand jaw safety is rendered inoperative, in a manner to be hereafter described, except during quadding and centering operations; for lines that are to be cast regularly (i. e. not quadded or centered), the right-hand jaw safety serves to release the pump plunger stop in the usual way.

A circuit of the entire electrical system is shown in Figs. 36 and 36A (the circuit was broken into two figures for convenience) wherein voltages of 6.3 and 24 A. C. are shown as being tapped off the low potential side of a transformer 142, the latter being converted into direct current by rectifiers 143 and 150. When the machine is to be manually operated and the quadding and centering operations controlled by the push buttons, the switch 64 of the control box 63 is opened, as shown in Fig. 36. If the machine then is to be operated regularly, the appropriate button may be depressed to release the four other buttons and to open the switches 60^b to 60^f, inclusive.

Assuming, however, that a particular line, having been composed in the assembler 2, is to be quadded with the right-hand jaw, the appropriate button 60-C is thereupon depressed, closing a switch 60^c which conditions a circuit for the energization of a relay 153 in the memory unit. When the line of matrices has been transferred to the first elevator 8 and the latter begins its descent, the switch 182 is closed by the rotation of the first elevator cam 8^a to complete the circuit for the relay 153 and to close the contacts 160, 168, 175 and 181 associated therewith, the circuit being traceable from +D. C. of the rectifier 150 through switch 182 and the closed contacts 178 and 178^b to the relay 153 and back to -D. C. of the rectifier. The contact 160 is a "make-before-break" type and a new holding circuit for the relay 153 is completed from +D. C. of the rectifier 150 through the switch 184 and the contact 160 to the relay 153 and thence back to -D. C. of the rectifier, so that the switch 182 may be opened by the further rotation of the cam 8^a. The operating circuits for the solenoids A and C are thus completed, the former through the contact 168 and the latter through the contact 175; the plunger B¹ of the unenergized relay B will, therefore, permit a slight downward movement of the slide 67 to rotate the control collar 21 for right-jaw quadding, all in the manner hereinbefore described. The closing of the bottom contact 180 completes a circuit to put A. C. voltage across the rectifier 143, thereby conditioning the left-hand jaw safety device for operation. After the completion of the casting operation, the matrices are carried upward by the first elevator 8 for purposes of distribution, and the first elevator cam 8^a opens the normally closed switch 184 to break the holding circuit for the relay 153.

For assembled lines that are to be centered, the push button 60-D is depressed and a switch 70^d closed to condition the relay 152 for operation, the circuit being completed, as before, by the closing of switch 182 in the rotation of the first elevator cam 8^a. When relay 152 is energized the contacts 159, 167, 174 and 179 are

closed, and, here again, a new holding circuit for the relay is completed through the switch 184 and the contact 159, so that the switch 182 can be opened. The closing of contacts 167 and 174 energize, respectively, the solenoids A and B; hence, the downward movement of the slide 67 will be controlled by the plunger C¹ of the solenoid C, and the control collar 21 adjusted to centering position. Here again, the left-hand jaw safety device is rendered operative by the closing of the contact 179, and, after casting, the switch 184 opened by the further rotation of the first elevator cam to break the holding circuit for relay 152.

15 The depression of the appropriate push button 60-E for left-jaw quadding closes the switches 60^e and 60^f, and when the switch 182 is closed by the rotation of the first elevator cam, both of the relays 152 and 153 are operated to effect the energization of all three solenoids A, B and C, the closing of the contacts 179 and 180 serving to condition the left-hand jaw safety device for operation; and, finally, the holding circuit for the relays 152 and 153 is broken during the ascent of the line after the casting operation by the opening of the switch 184 by the cam 8^a.

The fifth push button 60-B, designated "automatic," adapted to close the switch 60^b, permits full lines to be cast regularly and lines shorter than full length by a predetermined amount to be right-jaw quadded. Thus, when a line which is too short to close the pre-set switch 86 of the line measuring device 80, a circuit will be completed, as soon as the switch 182 is closed by the rotation of the cam 8^a, from +D. C. of the rectifier 150 through switches 182 and 60^b and the closed contacts 181^b and 181 and the contact 166 of the relay 151 (said contact normally being closed when the relay 151 is inoperative) to the relay 153 and -D. C. of the rectifier. The manner in which the relay 153 effects the right-jaw quad setting of the control collar 21 has been described above with respect to regular right-jaw quadding. If, on the other hand, the line is long enough to close the switch 86 of the line measuring device, the relay 151 is energized and the contact 166 opened to prevent the operation of relay 153. The line will, therefore, be cast regularly.

When the machine is to be operated by a Teletypesetter unit under the control of a tape, the switch 64, conveniently located on the control panel 60, is closed and a circuit completed from the D. C. side of the rectifier 150 to energize the relay 158; the closing of the relay 158 closes the contacts 165 and 173, opens contacts 178-178^b and 181-181^b and closes 178-178^a and 181-181^a.

By way of preliminary explanation, it should be understood that the operation of the relay 158 conditions the entire memory relay section for use. When the machine is operated by a Teletypesetter unit, the quadding or centering signal for a particular line must be advanced through stages of the memory unit as the line is advanced closer to the casting position. Thus, as soon as the assembler 2 has delivered the line to the transfer fingers 4 and 5 and returns to line receiving position, the tape will operate to compose the next line; meanwhile, the preceding line may be waiting in the delivery channel 7, hence called a "waiting line," until after the first elevator 8 has carried up the next preceding line for distribution. Thus, two lines can be handled by the machine at a given time

while a third is in the process of composition. The need for separately storing the signals to effect the operations that go with each separate line should be apparent. Toward this end, the memory unit is provided with a first bank of relays 156 and 157 for registering the signal for the assembled line, a second bank 154 and 155 for storing the signal of a "waiting line," and a third bank 152 and 153, heretofore described, for controlling the selective operation of the solenoid A, B and C for the line about to be cast.

When a right-jaw quad signal is contained in the tape, a switch 190, associated with the Teletypesetter unit, is closed in a well known manner, completing a circuit for the energization of relay 156 from +D. C. of the rectifier 150 through the switch 190 and the closed contact 165 to relay 156 and thence back to -D. C. The operation of relay 156 closes the contacts 163 and 171, the contact 163 also being of the "make-before-break" type and serving to establish a holding circuit from +D. C. of the rectifier 150 through the closed switch 194 to the relay 156 and back to -D. C. before breaking the first holding circuit. At this time, the composed line is in the assembler 2 and ready for elevation to the transfer fingers 4 and 5. In response to a signal in the tape, the assembler 2 is raised by the rotation of a shaft 200 and a cam 201 (see Fig. 32) secured thereto, both parts of the standard Teletypesetter unit. For purposes of the present invention, however, and more particularly as means to actuate the switches 194 and 195 (the former being normally closed and the latter normally open), cams 202 and 203 are also fixed to the shaft 200 of the Teletypesetter unit. As the line is being raised in the assembler 2, therefore, the switch 195 is closed by the cam 203 to energize the relay 154 from +D. C. of the rectifier 150 through switch 195 and the closed contact 171. The further rotation of the shaft 200 and the cam 202 opens the switch 194 to break the holding circuit for the relay 156. The operation of the relay 154 closes the contacts 161, 169 and opens the contact 176 (the contact 161 again, being of the "make-before-break" type) to complete a new holding circuit for relay 154 from +D. C. of the rectifier 150 through the closed switch 183 associated with the first elevator cam 8^a and the closed contact 161 to the relay 154 back to -D. C. Thus, the left-jaw quad signal is stored in the relay 154 while the line is in "waiting" position but the relays 156 and 157 are free to receive the signal for the succeeding line. Finally, the "waiting" line is transferred to the first elevator 8 to be carried to the casting position, and, during this operation, the first elevator cam 8^a closes the switch 182, establishing a circuit from +D. C. of the rectifier 150 through switch 182 and closed contacts 178-178^a and 169 to the relay 153; the further rotation of the cam 8^a opens the switch 183 to break the holding circuit for relay 154. The operation of relay 153 to set the control collar 21 for right-jaw quadding has already been explained above.

The closing of switch 191 by a "centering" signal contained in the tape serves to energize relay 157 through the closed contact 173 and, as a result, the "make-before-break" contact 164 and the contact 172 are closed, the new holding circuit for relay 157 flowing from +D. C. of the rectifier 150 through the closed switch 194 and the closed contact 164. When the switch 195

is closed by the raising of the line in the assembler 2, the relay 155 is operated and the contacts 162 and 170 closed and the contact 177 opened. A new holding circuit is thereupon established for the relay 155 through the switch 183 and the closed contact 162. The further rotation of the shaft 200 opens the switch 194 and breaks the holding circuit for the relay 157. Finally, the switch 182 is closed by the elevator cam 8^a during the descent of the line to casting position to energize the relay 152 through the switch 182 and the closed contacts 178-178^a and the closed contact 170; the further rotation of the cam 8^a opens the switch 183 to break the holding circuit for the relay 155. The setting of the control collar 21 to centering position from the operation of relay 152 has been explained in connection with the push-button control.

The signal for left-jaw quadding in the control tape closes the switches 192 and 193, the former serving to energize the relay 156 through the closed contact 165 and the latter serving to energize the relay 157 through the closed contact 173. As explained above, the relays 156 and 157 are capable of establishing their own holding circuits through the closed switch 194 and the closed contacts 163 and 164 respectively, permitting the switches 192 and 193 to be immediately opened. The rotation of the shaft 200 to elevate the assembler 2 closes the switch 195, as explained above, to energize relay 154 through the closed contact 171 and the relay 155 through the closed contact 172. A holding circuit for relay 154 is established through the closed switch 183 and the closed contact 161; also, a holding circuit for relay 155 is established through the closed switch 183 and the contact 162. The further rotation of the shaft 200 opens the switch 194, breaking the holding circuits for relays 156 and 157 and leaving them clear. When the line has been delivered to the first elevator 8 for transit to the casting position, the switch 182 is closed by the rotation of the first elevator cam 8^a and operates relays 152 and 153, the former through the closed contacts 178-178^a and 170, and the latter through the closed contacts 178-178^a and 169; the switch 183 is thereupon opened to clear the relays 154 and 155. As explained in connection with the push-button control, the relays 152 and 153 operate all three solenoids A, B and C for left-jaw quadding.

If a short line is composed in the assembler 2 under the control of a tape and no quadding or centering signal is contained therein, the short line fails to close the switch 86 of the line measuring device 80 as it travels to the left in the delivery channel 7; consequently, when the switch 182 is closed by the cam 8^a, as the line is being lowered to casting position, the relay 153 is operated by a flow of current from +D. C. of rectifier 150 through switch 182 and the closed contacts 178-178^a, 176, 177, 181-181 and 166 through relay 153 to -D. C. of the said rectifier. As previously explained, the contact 166 is closed when the relay 151 is inoperative; hence, when a full line is sent through for regular casting, the switch 86 is closed, thereby energizing the relay 151 and opening the contact 166. Since the right-jaw quadding circuit is completed through the contact 166 to the relay 153, the control rod 14 is maintained in its regular position, as shown in Fig. 6.

Thus far, the operation of the push-button and Teletypesetter controls for the present quadding and centering mechanism have been de-

scribed with reference to the light and dark lines of the circuit diagram shown in Figs. 36 and 36A. If it is desired to equip a machine with only the push-button control (or, in other words, to remove all of the circuit shown in light lines), jumpers 210 and 211 can be provided, as shown in Fig. 36A, and the operation will be identical with that described above with reference to the push-button control.

The circuit for the power lamp 62 can be traced from the 6.3 volt tap-off of the transformer 142 to the lamp 62 to ground and it can be seen that the lamp 62 will be lit whenever power is supplied to the transformer 142. Moreover, whenever the switch 64 is closed to operate the relay 158 for Teletypesetter operation, a circuit will be completed from the 6.3 volt tap-off to the lamp 63. Thus, the lamp 63 will be lit when the Teletypesetter control is conditioned for operation and will be extinguished when the switch 64 is opened for push-button control.

The various improvements have been shown and described in preferred form and by way of example, but obviously many variations and modifications may be made therein and in their mode of application without departing from the spirit of the invention. It is to be understood, therefore, that the invention is not to be limited to any specific form or embodiment except insofar as such limitations are specified in the appended claims.

What is claimed is:

1. In a typographical casting machine, the combination of a pair of line clamping jaws movable one toward the other for quadding, mechanism to effect such quadding movement of the jaw, mechanical means to condition said mechanism for a predetermined quadding operation, and electrical signal storing means to control said mechanical conditioning means.

2. In a typographical casting machine, the combination of a pair of line clamping jaws movable one toward the other for quadding, mechanism to effect such quadding movement of the jaw, mechanical means to condition said mechanism for a quadding operation or for a regular machine operation, as predetermined, and electrical signal storing means to control said mechanical conditioning means.

3. In a typographical casting machine, the combination of a pair of line clamping jaws movable each independently toward the other for quadding, mechanism to effect such quadding movements of the jaws, mechanical means to condition said mechanism for a quadding operation with either jaw, as predetermined, and electrical signal storing means to control said mechanical conditioning means.

4. In a typographical casting machine, the combination of a pair of line clamping jaws movable each independently toward the other for quadding, mechanism to effect such quadding movements of the jaws, mechanical means to condition said mechanism for a quadding operation with either jaw or for a regular machine operation, as predetermined, and electrical signal storing means to control said mechanical conditioning means.

5. In a typographical casting machine, the combination of a pair of line clamping jaws movable each independently toward the other for quadding or movable in unison toward each other for centering, mechanism to effect such quadding and centering movements of the jaws, mechanical means to condition said mechanism

for a quadding or centering operation, as predetermined, and electrical signal storing means to control said mechanical conditioning means.

6. In a typographical casting machine, the combination of a pair of line clamping jaws movable each independently toward the other for quadding or movable in unison toward each other for centering, mechanism to effect such quadding and centering movements of the jaws, 5 mechanical means to condition said mechanism for a quadding or centering operation or for a regular machine operation, as predetermined, and electrical signal storing means to control said mechanical conditioning means.

15 7. The combination according to claim 2, including means controlled by the length of the composed line to cause conditioning of the jaw moving mechanism for an automatic quadding with the right-hand jaw or for a regular machine operation.

10 8. The combination according to claim 1, wherein the electrical signal storing means includes a push button control switch to predetermine the conditioning of the jaw moving 20 mechanism.

15 9. The combination according to claim 1, wherein the electrical signal storing means includes a tape-operated control switch to predetermine the conditioning of the jaw moving 25 mechanism.

30 10. The combination according to claim 2, wherein the mechanical conditioning means includes a power-operated element adjustable to different predetermined positions under the control of the electrical signal storing means.

35 11. The combination according to claim 10, wherein the electrical signal storing means includes an electrically-controlled stop element which predetermines one position of the power-operated adjustable element.

40 12. The combination according to claim 10, wherein the mechanical conditioning means includes a spring for moving the adjustable element in one direction, and means actuated by the downward movement of the first elevator for moving said element in the opposite direction.

45 13. The combination according to claim 12, wherein the electrical signal storing means includes a fixed stop which locates the power-operated adjustable element in one position for a regular machine operation.

50 14. The combination according to claim 12, wherein the electrical signal storing means includes a fixed stop which locates the power-operated adjustable element in one position for quadding with the left-hand jaw.

55 15. The combination according to claim 12, wherein the electrical signal storing means includes a fixed stop which locates the power-operated adjustable element in one extreme position for a regular machine operation, and a second fixed stop which locates said element in another extreme position for quadding with the left-hand jaw.

60 16. The combination according to claim 6, wherein the mechanical conditioning means includes a power-operated element adjustable in opposite directions to different predetermined positions, and wherein the electrical signal storing means includes a fixed stop which locates said adjustable element in one extreme position for a regular machine operation, a second fixed stop which locates said element in another extreme position for quadding with the left-hand jaw, and two different electrically-controlled stop

19

elements which locate said element in intermediate positions, one for quadding with the right-hand jaw and the other for centering with both jaws.

17. The combination according to claim 5, wherein the electrical signal storing means includes a plurality of electrically-controlled stop elements which govern the conditioning of the jaw moving mechanism for quadding with the right-hand jaw, or for centering, as predetermined.

18. The combination according to claim 5, wherein the electrical signal storing means includes a plurality of electrically-controlled stop elements which govern the conditioning of the jaw moving mechanism for quadding with the right-hand jaw, for centering, or for quadding with the left-hand jaw, as predetermined.

19. The combination according to claim 1, including a line transporter movable to and from casting position and wherein the electrical signal storing means includes an electric circuit which is energized by the movement of the line transporter to casting position.

20. The combination according to claim 1, including a line transporter movable to and from casting position and wherein the electrical signal storing means includes an electric circuit which is energized by the movement of the line transporter to casting position, and which is deenergized by the movement of said transporter from casting position.

21. The combination according to claim 2, wherein the mechanical conditioning means normally occupies a neutral position with the jaw moving mechanism conditioned for a regular machine operation.

22. The combination according to claim 21, wherein the mechanical conditioning means is automatically restored to its neutral position after any quadding operation.

23. The combination according to claim 7, wherein the electrical signal storing means includes an electric circuit which when the jaw moving mechanism is conditioned for an automatic quadding operation with the right-hand jaw effects such quadding operation or permits a regular machine operation according to the length of the composed line.

24. In a typographical casting machine, the combination of a left-hand line clamping jaw and a right-hand line clamping jaw, the latter being movable toward the other for quadding, mechanism to effect such quadding movement of the jaw, means to condition said mechanism for an automatic quadding operation with the right-hand jaw or for a regular machine operation, and an electrical device governed by the length

20

of the composed line for controlling the operation of said conditioning means.

25. The combination according to claim 24, wherein the electrical device is normally inactive to accommodate lines of the proper justifying length for a regular machine operation and is automatically rendered active by composed lines of less than proper justifying length for a quadding operation with the right-hand jaw.

26. The combination according to claim 24, including a line transfer carriage, and wherein the electrical device is activated or deactivated by said carriage according to the length of the line being transferred.

27. In a typographical casting machine, the combination of a left-hand line clamping jaw and a right-hand line clamping jaw, the latter being movable toward the other for quadding, mechanism to effect such quadding movement of the jaw, means for disabling said jaw moving mechanism for a regular machine operation, and an electrical device governed by the length of the composed line for actuating said disabling mechanism.

28. The combination according to claim 24, including means for adjusting the electrical device to different operative positions to accommodate lines of different measure.

29. The combination according to claim 28, including additional means for adjusting the electrical device to off-measure positions to vary its control of the conditioning means according to the proper justifying length of any given line.

30. The combination according to claim 28, including means for adjusting the left-hand jaw relatively to the right-hand jaw to accommodate lines of different measure, and connections between said jaw adjusting means and the electrical device adjusting means to insure their corresponding adjustments.

31. The combination according to claim 30, including a line resistant, an adjustable stop therefor to accommodate lines of different measure, means for adjusting said stop, and connections between the line resistant stop adjusting means, electrical device adjusting means and the jaw adjusting means to insure their corresponding adjustment.

LOUIS ROSSETTO.
GINO F. SQUASSONI.
